APPARATUS FOR MAKING BAGS AND THE
LIKE

Adolph Potdevin, Garden City, and George E. Hampton, New York, N. Y., assignors to Potdevin Machine Company, Brooklyn, N. Y., a corporation of New York

Original application September 29, 1934, Serial No. 746,082. Divided and this application September 11, 1936, Serial No. 100,274

11 Claims. (CL 93—33)

This invention relates to an apparatus for making bags and is particularly directed to an apparatus for making bags of cellulose acetate, cellulose hydrate, glassine and the like.

5 This application is a division of our copending application Serial No. 746,082, filed September 29, 1934.

In one embodiment of our invention our improved apparatus is adapted, first, partially to 10 sever the bag material into bag lengths, this partial severing operation being followed by a second severing or cut-off operation; the apparatus of another embodiment of our invention partially severs the bag material, the partially severed 15 bag material is then torn apart and the top end of the bag length trimmed; while in still another embodiment of our invention the bag material is first partially cut off, followed by a finish cut-off and finally the top end of the bag length is 20 trimmed.

The trimming of the top end of the bag is of advantage in bags made of cellulose acetate and cellulose hydrate particularly, these materials being brittle so that they crack and tear readily. 25 If the tube material when being divided into bag lengths is cracked at the corner or corners, the trimming operation removes this cracked portion and cracking at the corners is eliminated.

In the accompanying drawings:

30 Fig. 1 is a sectional elevational view illustrating the apparatus constituting one embodiment of our invention;

Fig. 2 is a plan view of the same;

Fig. 3 illustrates one method of cutting out or 35 trimming the corners of the bag length;

Fig. 4 is an explanatory view illustrating the various steps followed with reference to the apparatus of Figs. 1 and 2;

Fig. 5 is a sectional elevational view of an 40 apparatus constituting another embodiment of our invention; and

Fig. 6 is an explanatory view with particular reference to the procedure followed in Fig. 5.

Referring first of all to Figs. 1, 2, 3 and 4. The 45 material from which the bags are to be made and which has been designated 1 as it is being fed to the machine is tubed as shown in Fig. 2. This tubing mechanism has not been illustrated in detail as the same may be well known commercial apparatus and its details are not claimed herein. It will be seen, however, from Figs. 1 and 2 that the material is tubed about a cut-off plate designated 2. This plate is a thin flat plate with upper and lower plane faces and is adapted to be reciprocated lengthwise of the

machine in timed relation with the other mechanism of the machine, as will be brought out fully hereinafter. The cut-off plate is adapted to be advanced in the direction of the travel of the material 1 by cut-off blades or cutters 3 and 4 mounted in cut-off rollers 5 and 6, respectively. The plate is retracted by a lever 7 pivoted at 8, one end of this lever extending through the tail of the cut-off plate as shown at 9.

The plate engaging end of the retracting lever 10 is positively actuated by cam 10 driven by a chain 11, for instance, it being understood, of course, that this cam or eccentric 10 is driven in timed relation with the rest of the machine so that the cut-off plate 2 will be retracted in the proper 15 timed relation to the operation of the cut-off blades or knives 3 and 4.

Between the tail or rear end of the cut-off plate 2 and the cut-off rollers 5 and 6 forwarding rollers 12 are provided. The function of these 20 forwarding rollers is to advance the tubed material continuously through the machine to the cut-off rollers.

The cutters 3 and 4 are set into the face of the rollers 5 and 6, respectively, and held in place 25 therein by screws 13, a land 14 being set into the face of each roller beside the cutter.

The cutters project slightly from the periphery of the rollers 5 and 6 and it will be appreciated that when the cut-off plate 2 is not being 30 advanced by the cutters 3 and 4 and the lands 14 it is free to be retracted positively by the reTRACTING lever 7.

We set the cut-off rollers with respect to each other so that the cutter 3, for example, will perform its cutting operation ahead of the cutter 4, thereby providing a projecting flap on the lower wall of the bag material. Obviously this order of operation of the cutters may be reversed. The cut-off rollers are adjustable circumferentially so as to vary the operation of the knives or cutters 3 and 4.

We wish to note that the cutters 3 and 4 are smooth edged, that is to say, are not serrated and are curved as viewed in plan, as illustrated in 45 Fig. 2, for instance.

It will be appreciated that when the leading cutter, the cutter 3 for example, engages the lower wall of the tubed material 1 it will roll over the plane face of the hard metal cut-off plate 50 2 to cut through the lower wall of the tubed material with a smooth rolling pinch cut. This cut is shown in Fig. 4 and designated 2'. The cut extends transversely of the tube from a point adjacent one edge of the tube to a point adjacent 55

the opposite edge. At this time the cut-off plate is bearing against the land 14 in the upper cut-off roller 6 so as to be carried forward or advanced at cutter speed during the cutting operation.

- 5 This operation is followed by a similar operation of the cutter 4 which rolls over the upper face of the plane face of the cut-off plate 2 partially to divide the upper wall of the tubed material 1 with a rolling pinch cut, as shown at 2" in Fig. 10 4, the plate 2 in this operation bearing against the land 14 in the lower roller 5 and moving forward at cutter speed. This is a partial severing or dividing operation and during this operation the bag tubing is in engagement with the rollers 15 15 which are just beyond the cutter rollers so as to keep the tubing from plugging.

As the cutters 3 and 4 engage only the plane faces of the cut-off plate 2 it will be appreciated, of course, that the edges of the tubed material 20 for a distance at least equal to the thickness of the cut-off plate are still uncut. We have shown this in Fig. 4 on somewhat of an exaggerated scale for the sake of clarity. In this embodiment of our invention the severing or dividing operation 25 is completed by cutters 18 carried by rollers 19 to which the tube is next advanced, these cutters cooperating with plain rollers 20. The cutters are so arranged as to cut through the tube at the corners as shown at 21 in Fig. 4. The 30 cutters 18 complete the severing operation as will be obvious.

The bag length up to this stage will have a projecting tab 21' at each corner of the leading end, this end later to be bottomed in finishing the 35 bag, while the trailing end, that is to say, the end which eventually is to be the top end of the finished bag will have a complementary cut-out.

Beyond the rollers 19 and 20 we provide pairs of rollers 22 and 23. The rollers 22 are equipped 40 with cams 24 for controlling cutter or punch operating levers 25 each of which is pivoted at 26. Lying below the advancing bag length is a die plate 27 and springs 28 have one end secured to this die plate and their other ends to the free 45 ends of the lever 25, as seen in Fig. 1.

Attached to the levers 25 are die plungers 29 cooperating with the die plate 27 to cut out or trim the corners of the trailing end of each bag length as shown at 30 in Figs. 2 and 4. The die plungers 29 may be so shaped that the notches 30 just referred to are of such a shape that when the end of the tube is opened up, as illustrated in Fig. 3, the bottom 31 of each cut-out is practically straight, that is to say, is substantially 50 at right angles to the edges 31' of the bag length. As a consequence there are no sharp corners for a tear to start in the top end of the tube, particularly at the point where the material is folded in tubing; and if in the operation of severing or 55 dividing the tubing into bag lengths initially the corners of the bag length become shattered or cracked these shattered or cracked portions will be removed by the cutters or plungers 29 in the trimming operation.

60 65 It will be seen, therefore, that the apparatus of this embodiment of our invention partially divides the tubed material by a rolling pinch cut followed by a completion of the dividing operation with the rotary cutters 18, this step being 70 followed by the trimming operation just described in which we cut out the corners of the trailing end of the bag length.

In the embodiment of our invention illustrated in Figs. 5 and 6, the final trimming operation is 75 eliminated. The tubed material is partially di-

vided with a rolling pinch cut by the cutters 3 and 4 acting in conjunction with the plate 2, the dividing operation being finished by the cutters 18. This leaves tabs 42' at the bottom end of each bag length with a complementary cut-back or cut-out 43 at the other end of each bag length.

We have found that our invention is particularly meritorious when dealing with materials such as cellulose acetate, cellulose hydrate, glassine and the like. These materials not only tear very readily but are quite brittle so that if the corners of the top end of the bag or bag length are splintered or cracked there is great likelihood of tearing at this point. By cutting back or trimming the corners of the tube as above explained the splintered material is removed and we are assured of smooth corners at the top end of each bag length.

We have described the cut-off plate 2 as being 20 positively retracted by the lever 7. It is to be understood, however, that if desired this cam-controlled lever mechanism may be substituted by the arrangement shown in the copending application of Paul Hunziker, Serial No. 647,502, filed December 16, 1932 in which the cut-off plate 25 is spring retracted.

It is to be understood also that die plungers 29 and 32 together with their cooperating plates 30 may be substituted by other mechanism if desired.

What we claim is:—

1. A bag making machine, comprising in combination a longitudinally movable plate extending lengthwise of the machine, tubing mechanism for tubing the material of the bag about said plate, a pair of rollers, cutters carried thereby, said cutters rolling in contact with said plate while the latter is in motion, intermittently to cut through the upper and lower walls of the tubing at bag length intervals, partially to divide 40 the tubing into bag lengths, and cutters adapted to finish the dividing operation.

2. A bag making machine, comprising in combination a movable cut-off plate having plane faces and extending lengthwise of the machine, 45 tubing mechanism for tubing the material of the bag about said cut-off plate while the latter is stationary, a pair of rollers, cutters carried thereby, said cutters rolling in contact with the plane faces of said plate while the latter is in motion, intermittently to cut through the upper and lower walls of the tubing on said plate at bag 50 length intervals, partially to divide the tubing into bag lengths by a pinch cut, and cutters for finishing the dividing operation.

3. A bag making machine, comprising in combination a longitudinally movable plate extending lengthwise of the machine, tubing mechanism for tubing the material about said plate, forwarding rollers for advancing the tube along said plate, a 60 pair of rollers in the path of said tubing, a cutter carried by each roller, said cutters rolling over the surface of said plate, while the latter is in motion, in contact with the tubing thereon, to cut through the upper and lower walls of the tubing, 65 partially to divide the tubing into bag lengths, and cutters thereafter engaging said tubing to finish the dividing operation.

4. A bag making machine, comprising in combination a movable cut-off plate having plane 70 faces and extending lengthwise of the machine, tubing mechanism for tubing the material of the bag about the stationary end of said plate, forwarding rollers for advancing the tubing along said plate, a pair of rollers in the path of said 75

5 tubing, a cutter carried by each roller, said cutters rolling over the plane faces of said plate, while the latter is in motion, in contact with the tubing thereon, to cut through the upper and lower walls of the tubing with a pinch cut, partially to divide the tubing into bag lengths, and cutters thereafter engaging the tubing to finish the dividing operation.

10 5. A bag making machine, comprising in combination a plate extending lengthwise of the machine, tubing mechanism for tubing the bag material about a stationary part of said plate, forwarding rollers for advancing the tubing along said plate, a pair of rollers in the path of the advancing tubing, a cutter carried by each roller, said cutters rolling over the surface of said plate, in contact with the tubing, partially to divide the tubing into bag lengths, said plate moving forward with the tubing during the operation of said 15 cutters, a cam actuated lever connected to said plate for returning the same to its initial position after said cutting operation, and cutters engaging said tubing after the operation of the first mentioned cutters to finish the dividing operation.

20 6. A bag making machine, comprising in combination a smooth faced metal cut-off plate extending lengthwise of the machine, tubing mechanism for tubing the bag material about a fixed 25 part of said plate, forwarding rollers for advancing the tubing along said plate, a pair of rollers in the path of the advancing tubing, a cutter carried by each roller, said cutters rolling over the smooth faces of said plate in contact with the tubing, partially to divide the tubing by pinch cut into bag lengths, said plate being moved forward 30 with the tubing by said cutters and rollers during the operation of said cutters, a cam actuated lever for retracting said plate after said cutting operation, and cutters adapted to engage said tubing after the operation of said first mentioned cutters to complete the dividing operation.

35 7. A bag making machine, comprising in combination a tubing and cutting plate, tube forming mechanism adapted to tube the bag material about said plate, said plate being mounted on the tube forming mechanism and one end thereof having a slight reciprocating motion relatively thereto, forwarding means for advancing the tubing along said plate, a pair of rollers in the path 40 of the tubing, a cutter carried by each roller, said cutters engaging the wall of said tubing at bag length intervals and rolling over the surface of said movable plate to cut through the upper and lower walls of the tube, transversely thereof, partially to divide the tubing into bag lengths, said plate moving forward during such operation, a cam actuated lever for returning said plate to its initial position after each cutting operation, and 45 cutters adapted to engage the partially divided tubing after the operation of the first mentioned cutters to complete the dividing operation.

50 8. A bag making machine, comprising in com-

5 bination a plate extending lengthwise of the machine, tubing mechanism for tubing the material of the bag about said plate, a pair of rollers in the path of the advancing tubing, cutters carried thereby, said cutters rolling in contact with said plate, to cut through the upper and lower walls of the tubing at bag length intervals, partially to divide the tubing into bag lengths, said cutters being so set or timed relatively that one cutter finishes its operation before the other cutter begins operating, and cutters adapted thereafter to engage the uncut portions of the tubing to complete the dividing operation.

10 9. A bag making machine, comprising in combination a smooth faced metal cut-off plate extending lengthwise of the machine, tubing mechanism for tubing the material of the bag about the stationary end of said plate, means for advancing the tubing, a pair of rollers in the path of the advancing tubing, cutters carried thereby, said cutters rolling in contact with the movable end of said plate, to cut through the upper and lower walls of the tubing with a pinch cut at bag length intervals, partially to divide the tubing into bag 15 lengths, said cutters being so set or timed relatively that one cutter finishes its operation before the other cutter begins operating, and cutters adapted thereafter to engage said tubing to complete the dividing operation.

20 10. A bag making machine, comprising in combination a plate extending lengthwise of the machine, tubing mechanism for tubing the material of the bag about the stationary end of said plate, a pair of rollers in the path of the tubing, cutters carried by said rollers, a land beside each cutter, said cutters rolling in contact with the movable end of said plate to cut through the upper and lower walls of the tubing at bag length intervals, partially to divide the tubing into bag lengths, said lands counteracting the pressure of the cutters on said plate during the operation of said cutters, and additional cutters later engaging said tubing for completing the dividing operation.

25 11. A bag making machine, comprising in combination a smooth faced metal cut-off plate extending lengthwise of the machine, tubing mechanism for tubing the material of the bag about the stationary end of said plate, means for advancing the tubing, a pair of rollers in the path of the tubing, cutters carried thereby, a land beside each cutter, said cutters rolling in contact with the smooth faces of the movable end of said plate to cut through the upper and lower walls of the tubing with a pinch cut at bag length intervals, partially to divide the tubing into bag 30 lengths, said lands counteracting the pressure of said cutters on said plate during the said operation of said cutters, and additional cutters later engaging the tubing for completing the dividing operation.
